UNITED STATES PATENT OFFICE.

JOHN FENTON, OF AUCKLAND, NEW ZEALAND.

FASTENER FOR HATS, BONNETS, AND THE LIKE.

No. 869,891.

Specification of Letters Patent.

Patented Nov. 5, 1907.

Application filed May 7, 1906. Serial No. 315,505.

To all whom it may concern:

Be it known that I, JOHN FENTON, a subject of His Majesty the King of Great Britain and Ireland, residing at Grey Lynn, Auckland, in the colony of New Zealand, have invented certain new and useful Improvements Relating to Fasteners for Hats, Bonnets, and the Like, of which the following is a specification.

According to this invention the guide instead of being fixed to the hat is made in the form of a perforated 10 plate which is adapted to slide in a frame having a comparatively long slot for the passage of the pins and which is secured to the hat upon the inside or outside of the crown. The advantage of this arrangement is that the 15 guide being free to move allows the pin to be passed through the hair at an angle on a horizontal plane to suit the desire of the wearer and the dressing of the wearer's hair.

The pins may be long enough to reach across the crown of the hat and take into a pad which is sewn upon 20 the opposite side. The pins terminate in a shank upon which is secured an ornamental head of any design.

Referring to the accompanying drawing.—Figure 1 is an inverted perspective plan of a hat showing my fastener in its operative position. Fig. 2 is an enlarged 25 perspective plan showing the fastener removed from the hat.

The frame 1 is sewn to the hat through holes 2 therein and has the longitudinal slot 12 and its top and bottom edges turned over to provide guides 3 and 4. A slide piece 5 is arranged to slide within the guides of the 30 frame and has a bridge 6 perforated to receive the pins 7, 8 and 9 which are secured in an ornamental knob 10. The middle pin 8 is straight while the outer members 7 and 9 normally tend to spread apart while being passed through the hair of the user. A pad 11 of felt or the like 35 is secured to the inside of the hat and if desired the points of the pins may be forced into it for additional security.

What I do claim and desire to secure by Letters Patent of the United States is:—

A device for the purpose indicated comprising a frame 40 adapted to be secured to a hat having a horizontal slot and guides upon its top and bottom edges, a slide piece adapted to work horizontally in said guides and pins secured in a knob and passing through said slide substantially as specified.

In testimony whereof I have signed my name to this specification in the presence of two witnesses.

JOHN FENTON.
